(57) **CLAIM**

The ornamental design for a burst-mode optical transceiver, as shown and described.

DESCRIPTION

FIG. 1 is a top exploded perspective view of the burst-mode optical transceiver, showing my new design;

FIG. 2 is a bottom exploded perspective view thereof;

FIG. 3 is a top elevational view of the upper housing thereof;

FIG. 4 is a top elevational view of the lower housing thereof; FIG. 5 is a top perspective view of the assembled upper and lower housings;

FIG. 6 is a bottom perspective view thereof of the assembled upper and lower housings;

FIG. 7 is a top elevational view thereof;

FIG. 8 is a bottom elevational view thereof;

FIG. 9 is a front elevational view thereof;

FIG. 10 is a rear elevational view thereof;

FIG. 11 is a right side elevational view thereof; and,

FIG. 12 is a left side elevational view thereof.

The broken line portion of the figure drawings is included to show unclaimed subject matter only and forms no part of the claimed design.
